UNITED STATES PATENT OFFICE.

THOMAS TUGBY, OF NIAGARA FALLS, NEW YORK.

DESIGN FOR A BROOCH-PIN.

SPECIFICATION forming part of Design No. 21,759, dated August 9, 1892.

Application filed June 21, 1892. Serial No. 437,525. Term of patent 7 years.

To all whom it may concern:

Be it known that I, THOMAS TUGBY, of Niagara Falls, in the county of Niagara and State of New York, have invented and produced a new and original Design for a Brooch-Pin, of which the following is a specification, reference being had to the accompanying drawings, in which—

Figures 1 and 2 represent, respectively, a perspective view and an inverted plan view of a pin embodying my new design.

The part A has substantially the form of a longitudinal half of a prolate ellipsoid. At one end of the same is a small hemispherical

body B. Beneath these parts A B is a flat 15 plate C, having points at one end. Beneath said plate C is a spider-like figure D, composed of radiating arms, whose ends project beyond the edge of the plate and have an upward bend. 20

I claim—

The design for a brooch-pin, herein shown and described.

THOMAS TUGBY.
